UNITED STATES PATENT OFFICE.

ROBERT SHAND, OF PHILADELPHIA, PENNSYLVANIA.

LOOM-SHUTTLE.

SPECIFICATION forming part of Letters Patent No. 339,941, dated April 13, 1886.

Application filed June 29, 1885. Serial No. 170,098. (No model.)

To all whom it may concern:

Be it known that I, ROBERT SHAND, a citizen of the United States, and a resident of Philadelphia, Pennsylvania, have invented 5 certain Improvements in Loom-Shuttles, of which the following is a specification.

My invention relates to that class of loom-shuttles in which the cop is placed directly in the chamber of the shuttle and held therein 10 by a cover-strip, my invention consisting of an improved elastic attachment for this cover-strip, with the object of dispensing with the strips of elastic fabric which are now extensively employed.

15 In the accompanying drawings, Figure 1 is a longitudinal section of a loom-shuttle with my improvements; Fig. 2, a plan view of the same; Fig. 3, a detached perspective view of the elastic attachment for the cover-strip detached from the shuttle.

20 A represents the body of the shuttle, which is provided near one end with the usual delivery-eye, *a*, and has formed in it a chamber, *b*, for the reception of the cop *x*, which delivers from the end, as usual, and is confined in the chamber *b* by the cover-strap *B*, the cop being prevented from slipping longitudinally by reason of the serrated shell of the shuttle-body.

25 Usually the strap *B* consists of a web of elastic fabric secured at one end to the shuttle-body, and having at the opposite end a hook, *d*, adapted to a transverse rod or bar, *f*, in the shuttle. The objection to a retaining-strap of this character is that it is rapidly worn out, and has a tendency to lose or partially lose its elasticity after a short time. To overcome 30 these objections, I use a retaining-strap of leather or other inelastic material, and provide an elastic connection for this strap at one end. This connection, as shown in Figs. 1 to 3, comprises a drum, *g*, free to turn on a transverse pin, *h*, driven through the shuttle-body, the drum being acted upon by a spring, *i*, 35 which is coiled around the reduced end of said drum, one end of the spring being connected to the drum and the other end to a plate, *m*, having beveled edges for adaptation to a dovetailed recess formed in the shuttle-body near 40 one end of the chamber *b*.

The tendency of the spring *i* is to turn the

drum in the direction of the arrow, Fig. 1, and thus impart tension to the strap *B*, and cause the latter to bear firmly upon the cop *x*, the drum yielding, however, when it is desired to 55 release the hook *d* from the bar *f*, in order to lift the strap to remove the cop or insert a fresh one.

The plate *m* may, if desired, be dispensed with, and the outer end of the spring *i* adapted 60 to an opening formed directly in the shuttle-body; but the use of the plate is preferred, as it provides a better bearing for the end of the spring, and permits the fitting together of the parts before their application to the shuttle, 65 all that is then necessary being to secure them in position by inserting the pin *h*.

I am aware that a spring-drum and strap have been used for the purpose of drawing a block along a shuttle-spindle and forcing a cop 70 from the same; but this is essentially different from my invention, no spindle or sliding block being employed in my shuttle, and the function of the strap *B* being simply to serve as a cover for the cop and retain the latter in 75 place. When the sliding block is employed for acting on one end of the cop, the opposite or delivering end of the same is jammed against the end of the recess in the shuttle-body, and the threads are thereby subjected to friction, 80 tending to retard their free delivery, whereas in my improved shuttle that end of the strap opposite the drum has a hooked catch adapted to a retaining-pin in the shuttle; hence the tension of the strap has no such effect as that 85 above described.

I claim as my invention—

1. The combination of a shuttle-body recessed for the reception of a cop, a drum, *g*, hung to a spindle near one end of said recess, 90 a retainer, *f*, near the opposite end of the same, a spring acting upon the drum, and a flexible but inelastic strap connected at one end to the drum and having at the opposite end a catch adapted to the retainer *f*, all substantially 95 as specified.

2. The combination of the shuttle-body having a recess for the reception of the cop, a lateral recess communicating with the said cop-receiving recess near one end of the same, a 100 cop-holding strap, *B*, a retaining-pin, *f*, for one end of said strap, a drum, *g*, to which the

other end of the strap is connected, a plate, *m*, adapted to the lateral recess of the shuttle-body, a spring connected at one end to the drum and at the opposite end to said plate, 5 and a pin, *h*, passing through openings in the drum, plate, and shuttle-body, and serving as a spindle for the drum and as a retainer for the plate *m*, all substantially as specified.

In testimony whereof I have signed my name to this specification in the presence of two sub- 10 scribing witnesses.

ROBERT SHAND.
